CLAIM

The ornamental design for a towing link assembly, as shown and described.

DESCRIPTION

FIG. 1 is a perspective view of an embodiment of a towing link assembly showing my new design, in a coupled configuration, with the handle in a raised position;

FIG. 2 is an orthographic left side view thereof;

FIG. 3 is an orthographic right side view thereof;

FIG. 4 is an orthographic top view thereof;

FIG. 5 is an orthographic rear view thereof;

FIG. 6 is an orthographic front view thereof; and,

FIG. 7 is an orthographic bottom view thereof.

The dash-dot lines shown in FIGS. 1-7 represent boundary lines between claimed and unclaimed subject matter, with the dash-dot lines themselves representing unclaimed subject matter. The broken lines in FIGS. 1-7 represent environmental subject matter and form no part of the claimed design.
